FENCE GATE

Clarence M. Elson, Lake Preston, S. Dak.

Application June 19, 1937, Serial No. 149,090

5 Claims. (Cl. 39—82)

This invention relates to fence gates. It is particularly directed to a hinged fence gate and the like articles.

An object of this invention is to provide a gate of the character described, hinged to a post by an improved hinge which can quickly and easily be installed, and permit the gate to be removed from the hinge by the removal of a single bolt.

10 A further object of this invention is to provide a gate of the character described hinged on a hinge which will permit the gate to be raised at one end, to permit hogs and sheep to pass under, but to turn cattle and horses.

15 A still further object is to provide a gate of the character described, so constructed that one end may easily be raised out of snow drifts and opened, the gate being hinged on a pin which may be easily removed so that the gate can easily be taken off and used in other places.

20 Yet another object of this invention is to provide a strong, durable and rugged gate of the character described which may easily be tilted or raised at one end, which shall be inexpensive to manufacture, and withal practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

35 In the accompanying drawing, in which is shown one of the various possible illustrative embodiments of this invention,

Fig. 1 is a front elevational view of a fence provided with a gate embodying the invention;

40 Fig. 2 is a cross-sectional view taken on line 2—2 of Fig. 1;

Fig. 3 is an enlarged cross-sectional view taken on line 3—3 of Fig. 2;

Fig. 4 is a view similar to Fig. 1, but showing 45 the gate tilted or raised upwardly at one end; and

Fig. 5 is a front elevational view of one end of the gate, and illustrating a modified construction.

Referring now in detail to the drawing, 10 designates a fence provided with a pair of 50 upstanding, parallel, spaced posts 11 and 12. Hinged to the post 12 as by hinge 13, is a gate 14. The hinge 13 comprises a bracket 15 having a vertical wall 16, from which there extends a horizontal wall 17 connected to the vertical wall 18 by a pair of parallel webs 19. The wall 16 is

formed with a bolt opening 19, and with an outwardly extending horizontal projection 20. The wall 17 is formed with a tapered through opening 21 decreasing in diameter toward the top. The bracket 15 is attached to the fence post 12 by means of a horizontal bolt 22 passing through the bolt opening 19. The projection 20 is received in an opening 20a in the post 12.

The gate 14 comprises a vertical member 25 and a pair of side vertical members 26 and 27 disposed inside the posts 11, 12. The members 25, 26 and 27 are interconnected by top and bottom parallel members 28 and intermediate parallel members 29. A diagonal member 30 may be attached across the members 25, 26 and 27. The members 28 extend beyond the members 26, 27 at both ends, as designated by numeral 28a to engage the posts 11 and 12. The upper of the members 29 extends beyond the member 27 at one end, as designated by numeral 29a.

Attached to the extending portion 29a of the member 29, as by bolt 32 is a bearing member 33 having a vertical through opening 34, and a ledge 35 extending beneath the bottom edge of said extending portion. The bearing member 33 rests on the portion 17 of the bracket 15, and the opening 34 is aligned with the opening 21. A washer 36 may be interposed between the bracket and the bearing. Extending through the openings 34, 21, and the opening in the washer 36, is a pin 38 having a head 39 at its upper end. A cotter pin 40 may be inserted within an opening at the bottom end of the pin 38.

It will now be understood that the gate 14 is hinged to the post 12 for swinging movement about a vertical axis. The gate may be lifted at one end as shown in Fig. 4, and the pin 34 and bearing member 33 will tilt with the gate. The gate may be removed by merely withdrawing the cotter pin 40 and lifting out the pin 38.

The gate 14 may be provided with a hook 42 at its outer end engaging an eyelet 43 on the post 11. Said post may be provided furthermore with a stop or projection 44 to hold the gate in horizontal position when closed. Another stop 45 may be provided to hold the gate in tilted position, to permit sheep and hogs to pass under, while turning back cattle and horses.

In Fig. 5 there is shown a modified form of gate. The gate 14a shown in Fig. 5 is constructed similarly to the gate 14 of Fig. 1, except that the members 29, and the top member 28 extend at the hinged end of the gate beyond post 12, and support a counterweight 50 made of a con- 55

crete or other suitable material to facilitate lifting of the gate to tilted position.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. In combination with a fence post, a bracket fixed thereto and formed with a tapered opening, a gate having a horizontal member, a bearing bolted to said member and having a ledge engaging the underside of said member, and formed with a vertical opening and a pin passing through the opening in the bearing and the tapered opening in the bracket, said pin having a head at its upper end above said bearing and provided with a cotter pin at its lower end below said tapered opening.

2. In combination with a fence post, a bracket fixed thereto and formed with an opening, a gate having a horizontal member, a bearing bolted to said member and having a ledge engaging the underside of said member and formed with a vertical opening, and a pin passing through the opening in the bearing and the opening in the bracket, said pin having a head at its upper end, and provided with a cotter pin at its lower end, the opening in the bracket being tapered and decreasing in diameter toward the top.

3. In combination with a fence post, a bracket having a vertical portion contacting the fence post and a horizontal portion extending from said fence post, means for fixing said bracket to said fence post, said horizontal portion of said bracket being formed with a tapered through opening,

a gate, a bearing member fixed to said gate and resting on said horizontal portion of said bracket, a pin passing through said bearing and through said tapered opening, said gate having an extending portion adapted to engage the fence post. 5

4. In combination with a fence post, a bracket having a vertical portion contacting the fence post and a horizontal portion extending from said fence post, means for fixing said bracket to said fence post, said horizontal portion of said bracket being formed with a tapered through opening, a gate, a bearing member fixed to said gate and resting on said horizontal portion of said bracket, a pin passing through said bearing and through said tapered opening, said gate 10 having a portion adapted to engage the fence post, and a weight on said portion of said gate. 15

5. In combination with a fence post, a bracket fixed thereto and having a vertical portion contacting said fence post, and a horizontal portion extending from said vertical portion, said vertical portion being formed with an opening to receive a bolt for attaching said bracket to said fence post, said fence post being formed with an opening, and said bracket having an integral projection extending into said opening to prevent rotation of said bracket about said bolt, the horizontal portion of said bracket being formed with a tapered through opening increasing in diameter toward the bottom, a gate having a horizontal member, a bearing bolted to said member and having a horizontal ledge engaging the underside of said member, said bearing being formed with a vertical through opening, and a pin passing through the opening in said bearing and the 30 tapered opening in said bracket, said pin having a head at its upper end contacting the upper end of said bearing, and a cotter pin at the lower end of said first pin and below the horizontal portion of said bracket, said gate having a portion extending beyond said bearing, and a counterweight on said portion of said gate. 35

CLARENCE M. ELSON.
